(No Model.)

H. H. MATT.
RAILROAD SWITCH.

No. 522,072.

Patented June 26, 1894.

THE NATIONAL LITHOGRAPHING COMPANY,
WASHINGTON, D. C.

UNITED STATES PATENT OFFICE.

HENREY H. MATT, OF LONG ISLAND CITY, NEW YORK.

RAILROAD-SWITCH.

SPECIFICATION forming part of Letters Patent No. 522,072, dated June 26, 1894.

Application filed March 17, 1894. Serial No. 504,000. (No model.)

To all whom it may concern:

Be it known that I, HENREY H. MATT, of Long Island City, in the county of Queens and State of New York, have invented a new and Improved Railroad-Switch, of which the following is a full, clear, and exact description.

My invention is an improvement in the class of railroad switches which are adapted to be operated from a car while in motion.

10 To these ends my invention consists of certain features of construction and combinations of parts, which will be hereinafter described and claimed.

Reference is to be had to the accompanying drawings, forming a part of this specification, in which similar figures of reference indicate corresponding parts in all the views.

Figure 1 is a plan view of a track provided with my improved switch and working mechanism. Fig. 2 is a longitudinal section on the line 2—2 of Fig. 1. Fig. 3 is a detail plan view of the lever mechanism for working the switch point; and Fig. 4 is a cross section on the line 4—4 of Fig. 1.

25 The railroad has the usual track rails 10 from which extend the siding rails 11, and at the junction of the track and siding rails is the usual swinging switch point 12 which is fulcrumed, as shown at 12^a on the bed plate 13, which on top is of the usual construction, but which has beneath its top surface a chamber 14 in which is fulcrumed a lever 15, one end of which is pivoted to the switch rail, as shown at 16 the pivot moving in a suitable slot in the bed plate 13, and the lever 15 is fulcrumed near the center on a pin 17 which enters a slot 18 in the lever.

To one end of the lever 15 is pivoted a connecting rod 19 which extends parallel with the track rails, and is at its opposite end pivoted to one end of a contact arm 20 which is

fulcrumed at the center, as shown at 21, and projects into parallel grooves 23 of the guide plate 22 on which is a rail section 10^a forming a continuation on one of the rails 10. The 45 pin 19^a connecting the rod 19 with the lever 20, moves in a slot 22^a in the plate 22 described above. The section 10^a is located midway on the plate 22 so that the guide grooves 23 come on each side of it. The lever 20 projects into these grooves, and it will be seen that when the lever is tilted laterally, the rod 19 is moved, the lever 15 oscillated and the switch point 12 thrown to one side or the other, this depending upon which end of the 55 lever 20 is struck.

The lever 20 may be operated by any suitable device which may be pushed down from a car so as to enter the grooves 23; and in order that the said devices may slide freely out of 60 the grooves they are provided with inclined bottoms at the ends, as shown at 24 in Fig. 2.

Having thus described my invention, I claim as new and desire to secure by Letters Patent—

65 The combination, with the bed plate having a chamber beneath it and the switch point pivoted on the bed plate, of a horizontally tilting lever fulcrumed in the chamber and connected at one end with the switch point, a 70 guide plate provided with parallel grooves and with a rail section arranged adjacent to the switch point, a lever fulcrumed in the guide plate and projecting into the grooves, and a connecting rod extending from the said 75 lever to the lever of the switch point, substantially as described.

HENREY H. MATT.
